UNITED STATES PATENT OFFICE.

GEORGE PURVIS, OF DETROIT, MICHIGAN.

BOILER BLOW-OFF AND CIRCULATING DEVICE.

Application filed November 29, 1918. Serial No. 264,433.

This invention relates to a blow-off and circulation device for steam boilers and more particularly to an arrangement of a selective valve thereof whereby the circulation part of the system may be cut out of use as desired, while the valve itself is balanced and is readily accessible and manipulatable from the exterior of the boiler.

The invention consists in the matters hereinafter set forth, and more particularly pointed out in the appended claims.

In the drawings,

Fig. 1 is a view in longitudinal section of a steam boiler of conventional type provided with a device that embodies features of the invention;

Fig. 2 is a view of the rear head of the boiler;

Fig. 3 is a view in detail, partly in elevation and partly in longitudinal section of a selective valve;

Fig. 4 is a view in cross section taken on or about line IV-IV of Fig. 3;

Fig. 5 is a view in detail of an indicating plate; and

Fig. 6 is a view in detail of a valve closure.

Referring to the drawings, a valve casing 1 is mounted in the head 2 of a boiler 3 of conventional type, either in a hand hole or other suitable opening. In preferred form the valve has a cylindrical body or casing 4 closed at the outer end and secured in the opening of the head 2 of the boiler by bolts 5 or studs 5 extending through the flange 6 of a fitting 7, and into the end of the casing, the flange being centered on an outlet nipple 8 of the casing which is preferably concentric therewith. The fitting leads to a blow-off valve 9 of suitable type. A rotatable stem 10 extends through the fitting and the bore of the nipple 8 into non-rotatable engagement with a valve closure 11, the inner end portion 12 of the stem being stepped in

an inner head 13 of the casing which is secured thereto by suitable studs 14 or the like. Preferably a squared or splined portion 15 of the stem engages into an opening in the end wall of the closure. The latter has a conoidal side wall 16 terminating in an outlet nipple 17 that is journaled in the counterbored opening of the outlet boss 8. A port 18 formed in the end wall 30 of the closure may be brought into register with an inlet opening of the wall 13 by rotation of the closure. This inlet opening is connected

by a conductor 19 with a suitable collecting nozzle 20 which is placed in the boiler where the sediment and mud usually collect, the nozzle being so disposed as to readily draw in the sediment under the ejector action of the device. Of course, more than one collector nozzle may be placed in the boiler and there may be as many openings in the end wall of the valve casing as there are nozzles and connecting pipes with each one of which the port 18 may be brought into register. A surface blow pan 21, which is at the normal water level of the boiler, is connected by a pipe 22 with an opening in the valve casing 70 through the head wall 13, this opening being likewise arranged to be brought into register with the port 18. A circulating pipe 23, from the lower portion of the boiler shell leads to a lateral boss 24 in the valve casing 75 into the bore of which it opens. As shown in Figs. 2 and 4, casing 1 is provided with an upwardly-extending boss 31, this boss having an opening leading to the interior of the casing exteriorly to the valve closure, the upper end of the boss being below the normal water level of the boiler as indicated in Fig. 2, the boss being below the level of blow-pan 21. This places the space exterior 80 of the valve closure in communication with the bottom of the boiler through pipe 23 and with the upper water level portion through the boss 31. Consequently it produces a practically balanced action on the valve closure. Whenever it is desired to cut the 85 circulating pipe out of action, a lateral lug 25 on the closure is arranged to be brought into register with the opening through the boss 24, thereby sealing the latter. A suitable handle 26 manipulates the stem 10 and an index pointer 27 sweeping a dial plate 28 shows the position of the valve so that the same may be readily manipulated from the 90 boiler exterior.

As will be understood, the difference in 100 temperature between the water content at the inlet of pipe 23 and of the outlet of pipe 31 is necessarily of material amount, since the portion of the water below the grate line is substantially static while that of the upper 105 level is at the point of evaporation. In addition, however, pipe 23 is carried across the top of the fire box, thus bringing it into a zone where the walls of the box provide heating action of the water content, thus 110 materially increasing the temperature of the water content of pipe 23 at this point.

Hence, the variation in temperature between the inlet and outlet provided by this line of communication between the bottom of the boiler and the water level, acts to set up a circulation therein by reason of the tendency of the warmer portion to rise within the line, discharging through boss 31—this being aided by the location of the horizontal portion of pipe 23—with the result that the 5 inlet end of pipe 23 is constantly receiving a new supply from the static portion of the boiler content and disturbing the latter to this extent.

This action takes place whenever pipe 23 15 is not closed by lug 25. Obviously, this circulation action will tend to circulate sediment as well. Under ordinary running conditions the amount of sediment within the boiler which would be affected by this circulation is of such small amount as to be negligible, but where the vessel is in harbor where the water supply carries a much greater percentage, the feed of this water into the boiler introduces a much larger percentage, making it inadvisable to continue this circulation action during this period, the static condition being permitted to remain and permitting the sediment to settle where it can be blown out when the next 20 blow-off operation takes place. In other words, it is desirable to prevent this circulation action during the period when the vessel is entering or leaving port, during which the backing and forward movements are had 25 with the bottom of the vessel close to the bottom of the channel.

As will be seen the arrangement of the circulation means is such as to produce somewhat of a thermo-siphonic action through 30 the fact that the content of the circulating passage varies practically from water to steam, the entrance to the passage being below the line of evaporation and the outlet at substantially the point of greatest evaporation, with the fire box wall itself aiding in 35 enhancing the circulating action.

It will be understood, of course, that the length of boss 31 will depend on the position of the casing in the boiler relative to 40 the normal water level, and where such posi-

tion brings the casing closer to the level than that shown, the boss may be omitted and the perforation through the casing wall be utilized, it being preferred that the outlet for the circulation be slightly below the normal 45 water level as shown.

Obviously, changes in the details of construction may be made without departing from the spirit of my invention and I do not care to limit my self to any particular form 50 or arrangement of parts.

What I claim is:—

1. The combination with a boiler, of valve means mounted thereon and having a chamber therein, a blow off pipe and a discharge 55 pipe communicating with each other through the valve means and leading therefrom respectively to the bottom of the boiler and to a point exterior of the boiler, means for establishing circulation within the boiler 60 and comprising conduits leading from said chamber substantially to the bottom and to the normal water level line of the boiler respectively, said valve means comprising a movable element having portions adapted 65 respectively to close said blow off pipe and to interrupt circulation through said conduits.

2. The combination with a boiler of a valve casing mounted thereon and having a chamber therein, a valve in said casing, draw 70 off pipes leading from said casing and respectively having ends opening substantially at the bottom and the normal water level line of the boiler, a discharge pipe leading from said casing to a point outside the boiler, means for promoting circulation within said 75 boiler and comprising conduits communicating with each other through said chamber and leading therefrom to points adjacent to the normal water level line and the bottom 80 of the boiler, said valve being constructed and arranged to establish or interrupt communication between said discharge pipe and any of said draw off pipes, and to interrupt circulation through said chamber when one 85 of said draw off pipes and said discharge pipe are in communication.

In testimony whereof I affix my signature.

GEORGE PURVIS.
